(57) **CLAIM**

The ornamental design for a novelty packaging, as shown and described.

DESCRIPTION

FIG. 1 is a top, front and right-side perspective view of novelty packaging embodying my new design;

FIG. 2 is a top, front and right-side perspective view of the novelty packaging of FIG. 1, shown in an open configuration, wherein the representation of a watch therein in phantom forms no portion of the design;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.
